Writings low, Names of Nashua, N.H. Ass't to
Haiti horn & my of 13th day, 1851.
Letters Patent No: 362 - Dated April 1, 1851.

The Schedule referred to in these Letters Patent, and making part of the same.

To all Persons to whom these Presents shall come: Be it

Known, that I, Winslow Ames, of Nashua, in the County of Hillsborough and State of New Hampshire, have produced a new and useful ornamental design for a Parlor Grate, or Fire-place, and I do hereby declare that the same is fully represented in the accompanying drawings, in which, Fig. 1 denotes a top view; Fig. 2 a front elevation; and Fig. 3 a central, vertical and transverse section of it—the latter figure, being taken in the plane of the red lines marked on Figs. 1 and 2, as lines x, x.

The basket, or grate, is not shown in the drawings, as it forms no part of my design. The paneled blower is seen at A, in Figs. 1, 2, 3, the plate, or part of the fire-place, on which it rests, being shown at B. The top plate, or mantle, is seen at C, the upright front plate is represented at E, while the hearth, or bottom plate is shown at F, in the said figures. The ornaments of the various members are exhibited in bas-relief, or in incavo; all of which will be clearly understood from the drawings, by persons skilled in the art of pattern making.

What I claim, is the new and ornamental design for the top plate, the front plate, the base plate, and the blower, as represented in the drawings.

In testimony whereof, I have hereto set my signature, this fourteenth day of February, A.D. 1851.

Witnesses:

R. H. Eddy
A. Gould.
